UNITED STATES PATENT OFFICE.

CHAMPE S. ANDREWS, OF CHATTANOOGA, TENNESSEE.

MUSIC-ROLL BOX.

Application filed May 13, 1924. Serial No. 712,925.

This invention relates particularly to boxes of the type wherein the roll is supported in a slide which can be withdrawn from the front of the box.

5 Special objects of the invention are to provide a strong, durable and inexpensive "folding" box of this type, the parts of which can be blanked out in a flat form and then folded in the box shapes.

10 The accompanying drawings forming part of this specification illustrate a simple and practical embodiment of the invention wherein the desired objects are attained through certain novel features of construction, combinations and relations of parts and wherein:

Figure 1 is a plan view of the blank from which the slide is made up.

20 Figure 2 is a broken perspective view of the slide.

Figure 3 is a plan view of the box body blank.

25 Figure 4 is a perspective view of the completed box body looking at the open end of the same.

Figure 5 is a broken perspective view of the closed end of the box body.

Figure 6 is a side view illustrating the use of the boxes.

30 The box is made up of the two parts shown in Figures 2 and 4, an open top slide or tray 7 of a proper size to receive the music roll 8, Figure 6, and an open ended box body 9 of a size to receive the tray with an easy sliding fit.

The slide is made from a single blank 10 shown in detail in Figure 1, and similarly, the box body is made from a single blank 11, shown in detail in Figure 3.

40 The slide blank comprises an intermediate bottom portion 12 and two side portions 13 foldable on the lines 14, an inner end portion 15 foldable up from the bottom on line 16 and two end flaps 17 on the side walls foldable on line 18 into abutting relation, Figure 2, over the inner face of the end flap 15. The side walls 13 are shown as having longitudinal edge extensions 19 foldable on the lines 20 to form the doubled over upper edges of the slide. At the forward end of the bottom portion 12 a front end flap 21 is provided foldable up on the line 22 and front end side flaps 23 are also shown foldable on lines 24 to lap them over the inner face of the front flap as indicated in Figure 2.

In order that the front end of the slide may hinge downwardly, after the manner indicated in Figure 6, to open the slide for end withdrawal of the music roll, the side portions of the blank are shown as formed 60 with V-notches 25 cut therein substantially to the folding lines 14 at the bottom of the box, thereby providing transversely of the slide bottom, a hinge line 26. This hinged section is reenforced across the hinge line 65 by a layer 27 of fabric or other strong, flexible reinforcing material, which extends up the sides of the slide on both sides of the hinge line and on both sides of the wall, as indicated at 28 and 28^A in Figure 2. This construction not only reinforces the hinge line 26 but it also reinforces the corner formed by the slide bottom and wall and prevents breakage or cracking of the slide along the angle, either of the slide body 70 proper or of the extension.

This overlying reinforcement may be applied before the V-notches are cut in the blank and if desired may have an extension brought out through the front of the box 80 to provide a pull tab 29. In some cases this pull tab is simply in the form of a single or doubled strip of fabric secured by suitable adhesive to the forward bottom hinging portion of the slide.

The box body blank, Figure 3, is shown as comprising the bottom portion 30, having an end tab 31 foldable on line 32 to form the back of the box; a top portion 33 having an end tab 34 foldable on line 35 to overlie 90 the inner face of the outside end flap 31 and the side portions 36-37 foldable on lines 38-39 and 40-41 respectively and secured by the longitudinal flap extension 42 of side 37 glued or otherwise fastened in overlapping relation to the bottom portion 30. The side portions 36 and 37 have end flaps 43-44 foldable on the lines 45-46 to overlie the inner face of the inside end flap 34, Figure 5.

Both parts of the box may be cut out of a 100 suitable grade of cardboard, heavy enough to stand the wear but flexible enough to bend on the lines indicated, and which lines ordinarily will be suitably scored. The blanks are relatively simple and are easily set up by 105 bending them to the proper shape and gluing or otherwise suitably securing them in such form. The overlapping of the end flaps in the manner illustrated reinforces the ends of both the box body and the slide giving the 110

box sufficient rigidity and strength to support a stack of superposed boxes, as indicated in Figure 6.

The lapping of the side securing flap 42 over the bottom wall 30 of the box body, Figure 4, provides a track lifting the bottom of the slide above the box bottom and causing it to slide more freely in and out the box body. This lifting of the slide above 10 the box floor also provides clearance for the pull tab and forms a channel for escape of air, as the slide is operated.

In addition to being particularly simple and inexpensive, the box presents a neat and 15 attractive appearance and unlike the "made up" boxes, requires no special finishing or covering but is complete and ready for use as soon as the parts are set up. Also the construction disclosed provides a box body 20 in which the end is made up of three thicknesses of material and the ends of the slide are both made up of two full thicknesses of material. When the slide is within the box body the two end thicknesses of the slide 25 are added to the three end thicknesses of the body, giving the whole relatively great rigidity and strength.

I claim:—

1. A box for music rolls comprising a box 30 body open at the front end and closed at the back, a roll holding tray freely slidable into the box body to the extent permitted by the closed end of the latter, said sliding tray being open at the top for the free insertion 35 and removal of the roll and having end walls for restraining endwise movement of the roll, the side walls of the tray near the forward ends of the same being notched down to the bottom of the tray to enable 40 the forward end portion of the tray to hinge downwardly on a transverse line and a flexible reinforcement over said hinging portion and extending up the side walls of the slide on opposite sides of the notches to thereby prevent tearing of said hinging and 45 notched parts.

2. A box for music rolls comprising an open ended box body, a roll holding tray 50 freely slidable in the box body, said tray being open at the top for free removal and replacement of music rolls, the side walls of the tray near the forward ends of the same being cut down to the bottom of the tray to enable the forward end of the tray 55 to swing downwardly on a hinge line substantially transversely across the bottom and a flexible reinforcement overlying such hinging portion and extending up the separated side wall portions of the tray to prevent tearing of the hinge and separated side 60 wall portions and enable these parts in-

definitely to transmit the push and pull on the slide in the continued use of the same.

3. A box for music rolls comprising an open ended box body, a roll carrying tray 65 slideable therein having the side walls of the same near the front end of the tray cut down to the bottom of the tray to enable the front end portion of the tray to swing downwardly on a substantially transverse 70 hinge line and a flexible reinforcement extending over said hinge and adjoining portions of the tray to prevent tearing at the hinge and enable the parts indefinitely to transmit the push and pull applied to the 75 slide in the continued use of the box.

4. A box for music rolls comprising an open ended box body, a tray freely slideable in the box body and adapted to hold a single roll, said tray being open at the top for free 80 removal and replacement of a music roll, the side walls of the tray having notches extending to the tray bottom to provide a break in said side walls, to permit a portion of the tray to swing downwardly on a hinge 85 line at the bottom of said notches, said notches permitting the entry of fingers to freely grasp a roll in the tray.

5. A box for music rolls comprising a box body having an open end and an open 90 topped single roll holding tray freely slideable in the box body, the side walls of the tray near the forward end of the same having notches extending to the bottom of said walls providing a forward portion of the 95 tray adapted to swing downwardly on a hinge line in the box bottom at the bottom of said notches, said notches also permitting the entry of fingers to grasp a roll in the tray. 100

6. A tray slideable in an open ended box body and adapted to hold a single music roll, said tray comprising side walls having notches extending to the tray bottom to provide a forward portion of the tray adapted 105 to swing downwardly on a hinge line at the bottom of said notches, said notches permitting the entry of fingers to grasp a roll in the tray.

7. A tray slideable in an open ended box 110 body and adapted to hold a single music roll, comprising side walls having notches extending to the bottom of said walls to provide a break therein permitting a portion of the tray to swing downwardly on a hinge line at the bottom of said notches and said notches permitting the entry of fingers to grasp a roll in the tray. 115

Signed at New York in the county of New York and State of New York this 25th day 120 of April A. D. 1924.

CHAMPE S. ANDREWS.
